his attorney.

UNITED STATES PATENT OFFICE.

JAMES C. ARMOR, OF WEST VIEW BOROUGH, PENNSYLVANIA.

TRANSFORMER.

Application filed December 7, 1921. Serial No. 520,554.

To all whom it may concern:

Be it known that I, JAMES C. ARMOR, a citizen of the United States, and residing in the borough of West View, in the county of Allegheny and State of Pennsylvania, have invented or discovered new, useful, and Improved Transformers, of which the following is a specification.

My invention consists in a new and improved electrical transformer.

The object which I have in view is the provision of an alternating current transformer, more especially intended for use in electric welding.

Generally speaking my improved transformer is characterized by the slideable mounting of one of the windings, preferably the secondary winding, in relation to the other winding, whereby the amount of current induced in the secondary winding may be regulated to suit the task at hand. Means are provided whereby the workman may adjust the movable winding so that the transformer will deliver the amount of current desired.

I place the fixed winding above the slideable winding, whereby the force of gravity and the repulsion between the windings act in the same direction, and thus prevent chattering or movement of the winding. This insures uniformity of current.

Novel features of construction and arrangement of parts will appear from the following description.

In the accompanying drawings, Fig. 1 is a side elevation of a transformer embodying the principles of my invention, the casing or tank being shown in section; Fig. 2 is a plan view of the same with the cover removed; Fig. 3 is a sectional view taken along the line III—III in Fig. 1, and Fig. 4 is a sectional view of the top plate taken along the line IV—IV in Fig. 1.

The following is a detailed description of the drawings.

A represents the transformer core shown made up of a plurality of metal laminæ and about whose center leg 1 the primary coil B and the secondary coil C are both shown wound.

The laminæ are shown clamped together to form the core in the following manner. 2 represents a pair of opposed angle-bars which fit on the upper ends of the two outer laminæ and have their protruding ends clamped together by the reach bolts 3. 4

represents a pair of similar angle-bars for the bottom of the core clamped together by means of the reach bolts 5. 6 represents vertical reach bolts which connect each of the upper angle-bars with the corresponding lower angle-bars. When the transformer is contained in an outer container or tank, as at D, the ends of the vertical reach bolts 6 may extend through the bottom of the tank and be used for attaching the supporting bars 7 upon which the tank stands.

For the sake of illustration I have shown the transformer mounted in an oil-tight tank for oil-cooling, but if desired an open work or ventilated casing may be used.

The primary coil B is shown wound on the usual non-magnetic spool 8 surrounding the central leg 1 of the core A and it may be held in position on said core by any convenient means, as by the hangers 9 secured at their lower ends to the spool 8 and at their upper ends attached to the top angle-bars 2. The secondary winding C is wound on the spool 10 which is vertically slideable on the core leg 1, so that the secondary winding may be shifted in relation to the primary winding.

11 represents a pair of opposed hangers having their lower ends secured to the spool 10 and having their upper ends provided with the eyes 12 to which are secured the lower ends of the twin cables 13 which extend up past the primary winding B, and then inwardly through guide openings 14 in the side of a metal plate E which is positioned about the core A and preferably bolted to the top angle-bars 2. The openings are substantially tangential to the axis of a circular seat in the center of the plate E in which fits the pulley F having a grooved perimeter, the cables 13 being led partially around the perimeter of the pulley and their ends secured to said perimeter as by cap screws, as shown at 15 in Fig. 2. The pulley F is mounted on an axle 16 whose lower end is journaled in the circular hole 17 while its upper end extends through a hole in the lid G provided with a stuffing box 18 to prevent the escape of oil.

It is very advantageous to have the fixed winding above the slideable winding, as thus the forces of gravity and of repulsion between the windings act in the same direction and therefore there is an absence of chattering or movement on the part of the slideable winding which would be present were the

forces of gravity and repulsion exerted in opposite directions. In the latter case it would not be practical to freely suspend the 5 slideable winding, but rigid supporting means of a character to successfully resist the effect of the opposed forces would be required.

The lid G which incloses the tank D is bolted, as at 19, to the top edge flange of the 10 tank, and, as at 20, to the plate E.

The upper protruding end of the axle 16 has pinned thereon the cap collar 21 having a pair of horizontally extending and spaced apart pierced ears 22 between which is pivotally connected the inner end of the crank handle 23 which is provided, near its outer end with the depending knife lug 24 adapted to fit the teeth of an arc-shaped rack 25 mounted on the lid G and concentric with 20 the axle 16.

It is evident that by raising the handle to disengage the lug 24 from the rack 25, and turning the handle in the proper direction so as to wind up the cables 13 on the pulley F, 25 the secondary winding C will be moved toward the primary winding, thus increasing the amount of current in the secondary winding, while a reversed motion of the handle will lower the secondary winding 30 and thus reduce the amount of current therein.

When released, the handle drops and is automatically locked stationary by the engagement of its lug 24 with the rack 25.

35 It is evident that the workman is enabled to thus regulate the amount of current to a nicety to suit the piece of work in hand.

What I desire to claim is:—

1. In an alternating current transformer 40 for arc-welding and like purposes, the combination of a vertically disposed core, a primary winding and a secondary winding

mounted on said core, one above the other, the upper of said windings being stationary relative to said core while the lower of said 45 windings is movable on said core to permit current regulation, and means for supporting the lower winding in its adjusted position, whereby the forces of gravity and repulsion operate in the same direction on said lower 50 winding and chattering is prevented.

2. In an alternating current transformer for arc-welding and like purposes, the combination of a vertically disposed core, a primary winding and a secondary winding 55 mounted on said core, one above the other, the upper of said windings being stationary relative to said core but the lower winding being movable on said core to permit current regulation, and means for freely suspending the lower winding from above in its adjusted 60 position whereby the forces of gravity and repulsion work in the same direction and chattering is prevented.

3. In an alternating current transformer 65 for arc-welding and like purposes, the combination of a vertically disposed core, a primary winding and a secondary winding mounted on said core, one above the other, the upper winding being stationary on said 70 core while the lower winding is movable thereon toward and away from the upper winding for purposes of current regulation, flexible supporting members, a horizontal pulley centrally over the upper winding, to 75 which the upper ends of the flexible members are attached, a pair of guides for the said member arranged between the pulley and the lower winding and leading the said members tangentially to the pulley, and 80 means for rotating the pulley.

Signed at Pittsburgh, Pa., this 3rd day of December, 1921.

JAMES C. ARMOR.
